CLAIM

The ornamental design for window cleaning appliance as shown and described.

DESCRIPTION

1.1 Front, top left perspective view of the first embodiment

1.2 : Rear, bottom right perspective view

1.3 : Top

1.4 : Bottom

1.5 : Left

1.6 : Right

1.7 : Front

1.8 : Back

1.9 : Perspective view in a separated configuration

2.1 Front, top left perspective view of the second embodiment

2.2 : Rear, bottom right perspective view

2.3 : Top

2.4 : Bottom

2.5 : Left

2.6 : Right

2.7 : Front

2.8 : Back

The broken lines in the figures and the areas within the broken lines show portions of the product that form no part of the claimed design; The characteristic features lie in the window cleaning appliance incorporating the claimed design; The design is used as a cleaning utensil, intended to be attached to a window from both sides; Figs 1.1-1.2, 1.5-1.9 are exploded views, the brackets are not part of the claimed design.
